UNITED STATES PATENT OFFICE.

EDGAR P. ORRILL, OF AMERICUS, KANSAS.

IMPLEMENT HOLDER.

Application filed September 20, 1922. Serial No. 589,415.

To all whom it may concern:

Be it known that I, EDGAR P. ORRILL, a citizen of the United States, residing at Americus, in the county of Lyon and State 5 of Kansas, have invented certain new and useful Improvements in Implement Holders, of which the following is a specification, reference being had to the accompanying drawings.

10 This invention relates to display devices, and particularly to display devices for holding implements, such as brooms.

It is an object of the invention to provide a device of this character capable of being 15 easily moved about the floor of a store and arranged to support a plurality of implements in substantially pyramidal formation.

It is another object of the invention to 20 provide a device of this character including a stationary and movable standard, the movable standard being provided with means for clamping implements thereto.

It is a further object of the invention to 25 provide a device of this character including a stationary and movable standard, and wherein the means for supporting the movable standard on the stationary standard also serves as clamping means for the clamp- 30 ing members carried by the movable standard.

With these and other objects in view, the invention consists in the improved construction and arrangement of parts to be herein- 35 after more particularly described, fully claimed and illustrated in the accompanying drawings, in which:—

Figure 1 is a view in elevation of an im- 40 plement holder constructed in accordance with an embodiment of the invention;

Figure 2 is a top plan view; and

Figure 3 is a fragmentary sectional view showing the coupling of the movable standard to the stationary standard.

45 Referring to the drawings, 5 designates a stationary standard, having its lower end 6 threaded and disposed in a double T coupling 7. Extending from each of the remaining ways of the coupling 7 are supporting feet 8, the ends of said feet having elbows 9 connected thereto, while disposed within each elbow is a caster 10. By this means the standard or pipe 5 is disposed in a vertical position and may be moved about 50 to properly display the implements.

In connection with the stationary stand-

ard 5, a movable standard 11 is provided. This standard has its lower end provided with a plurality of slots 12 and its upper end provided with a plurality of slots 13. The 60 lower end as well as the upper end is threaded, the lower end being adapted to receive a coupling 14, while threaded in the lower portion of the coupling is a small length of tubing 15. This tubing is adapted to extend 65 into the stationary standard 5 to prevent disengagement of the movable standard 11.

In this instance the coupling 14 rests upon the upper end of the stationary standard 5 so as to permit rotary movement of the 70 standard 11 relative to the standard 5.

The upper end of the movable standard 11 is intended to support a holding member 16, said end of the member consisting of a rim 17 having spokes 18 extending inwardly 75 therefrom. The ends of the spokes are adapted to extend into the adjacent slots 13 of the standard 11 and are secured to the standard by means of a cap 18^a which is threaded on the end of the standard into 80 binding engagement with the ends of the spokes within the slots, thus permitting the holding member to rotate with the stationary standard 11. Projecting from the periphery of the rim 17 is a plurality of loop 85 socket members 19 adapted to receive the upper ends of the implements such as brooms. The size of the rim 17 of the holding member is sufficient to permit the implements to be maintained in pyramidal 90 formation without causing the ends of the implements to come in contact with each other.

In connection with the holding member 17, a main holding and clamping member 20 95 is provided, said member including an inner rim 21 having spokes 22 extending inwardly therefrom. The spokes 22 have their ends disposed within the slots 12 of the standards 11 and are firmly clamped to the 100 standard 11 by the coupling 14. The coupling 14 is intended to urge the spokes in engagement with the ends of the slots. Carried by the rim 21 is a plurality of clamping members 23, each clamping member consisting of a length of resilient wire bent at its central portion to provide arms 24 and 25, said arms converging with respect to each other. The central portions of said arms are coiled around an outer rim member 26 which 110 is spaced from the inner rim member. The end portions of the arms 25 are then ex-

tended to the inner rim member and coiled about said inner rim member.

By this means the arms 24 and 25 of each clamping member cooperate to provide jaws 5 for the clamping of implements therebetween. It is of course obvious that the portion of each arm coiled about the outer rim member 26 is yieldable so as to permit the jaws to adjust themselves in accordance with 10 the size of the article clamped by the arms 24 and 25. To further insure the unitary movement of the holding members 16 and 20, braces 27 are provided, said braces extending from the upper holding member 16 to 15 the outer rim 26 of the main holding member. By this arrangement the holding members 16 and 20 rotate with the movable standard 11 on the stationary standard 5 so as to permit the implements carried by the 20 holder to be brought into view without the necessity of the customer or purchaser walking around the holder in order to view the implements.

From the foregoing it will be readily seen 25 that this invention provides a novel form of implement holder particularly adapted for holding brooms in an attractive position and wherein the brooms may be positively held without damage to the broom head. In addition to this the novel arrangement of the 30 clamping arms is such that a large number of implements may be supported by a holder relatively small in size and wherein the

brooms practically conceal all portions of the holder disposed inwardly of the rims of 35 the holding members, so that in addition to preventing shop wear of the brooms or implements, the holder adds to the appearance of the store. All of these features are possessed by a device which is composed of only 40 a small number of simple parts.

What is claimed is:—

An implement holder comprising a base, a stationary standard, a movable standard 45 movably mounted on the stationary standard, an upper holding member journaled on the top of the movable standard, a lower holding member comprising a wheel carried by the lower portion of the movable standard, a rim larger in diameter than the wheel 50 and disposed in annular spaced relation to the wheel, a plurality of clamping members, each member consisting of a length of wire bent substantially U-shaped, the central portion of each wire being coiled about the rim 55 member, the extremities of said end portions being extended inwardly and coiled about the rim of the wheel, each of said clamping members being disposed at spaced intervals annularly of the rim, each clamping member coacting with the adjacent clamping member to hold an article therebetween.

In testimony whereof I hereunto affix my signature.

EDGAR P. ORRILL.
